(57) **CLAIM**

The ornamental design for an escutcheon plate for an enclosure, as shown and described.

DESCRIPTION

FIG. 1 is a left front perspective view of an escutcheon plate for an enclosure showing my new design;

FIG. 2 is a front view thereof;

FIG. 3 is a right side view thereof;

FIG. 4 is a left side view thereof;

FIG. 5 is a top view thereof; and,

FIG. 6 is a bottom view thereof.

The portions of the drawings shown in broken lines represent environmental structure and form no part of the claimed design.
